ASSIGNORS TO WESTERN ELECTRIC COMPANY, INCORPORATED, OF NEW YORK, N. Y.,
A CORPORATION OF NEW YORK.

MECHANISM FOR REMOVING BURS.

1,296,154.

Specification of Letters Patent.

Patented Mar. 4, 1919.

Application filed November 24, 1917. Serial No. 203,774.

To all whom it may concern:

Be it known that we, ISAAC W. ATCHISON and FREDERICK M. STEIMER, citizens of the United States, residing at Cicero, in the county of Cook and State of Illinois, and Chicago, in the county of Cook and State of Illinois, respectively, have invented certain new and useful Improvements in Mechanism for Removing Burs, of which the following is a full, clear, concise, and exact description.

This invention relates to a mechanism for removing burs, and more particularly to a bur removing mechanism applicable for use with a thread rolling machine whereby the operation of rolling the thread on the blank and removing the burs from the blank are performed simultaneously.

A rather frequent incident in the manufacture of screw blanks is the production of burs and fins on the screw heads of the blanks. These burs and fins are objectionable and must be removed from the screw heads whenever the completed screws are to be used for the more finished and better grades of work. Consequently it has been necessary to submit such screw blanks to a burring operation after the screw blanks have been completely formed and finished. In the manufacture of slotted screws additional burs are produced in the slotting operation at the point where the slotting saw leaves the screw head. This invention is therefore not limited for use with a thread rolling machine, but may be used in combination with a screw slotting machine or any other mechanism which generates burs on the articles operated upon, which burs must be removed.

It is the object of this invention to combine the operation of thread rolling, or any other equivalent operation, and blank burring, the preferred form of the invention herein illustrated and described residing in the production of an improved attachment applicable to a thread rolling machine which will automatically remove the fins or burs attached to the heads of the screw blanks as said blanks are rolled between the thread rolling dies.

The invention is illustrated in the accompanying drawings, in which:

Figure 1 is a plan view of a portion of a thread rolling machine and shows the sta-

tionary and removable dies thereof together with the burring attachment secured to the frame of the machine;

Fig. 2 is an end elevation thereof;

Fig. 3 is a section on the line 3—3 of Fig. 1 looking in the direction of the arrows;

Fig. 4 is a section on the line 4—4 of Fig. 1 looking in the direction of the arrows;

Fig. 5 is an alternative form of burring attachment;

Fig. 6 is a portion of the cutting surface of the attachment shown in Fig. 5 showing the cutting edges or teeth thereof;

Fig. 7 is a section similar to Fig. 3 showing the alternative form of burring attachment illustrated in Fig. 5 secured to the machine, and

Figs. 8, 9, 10, and 11 are samples of screw blanks and illustrate the type of burs and fins produced on these blanks in the forming and slotting operations.

In the preferred form of the invention illustrated in the figures, the apparatus has been adjusted for the burring operation on flat headed screws such as illustrated in Fig. 8. The burring attachment may be readily adjusted, however, for burring operations on screw blanks of any type, as for example, those illustrated in Figs. 9 to 11 inclusive, as will be hereinafter described.

For the purpose of illustrating this invention, any type of standard thread rolling machine can be used, to any of which the burring mechanism may be readily attached. In Figs. 1, 2, 3, 4, and 7 a section of a thread rolling machine including a stationary die 10 and a movable die 11 has been shown. The stationary die 10 is suitably mounted in the frame of the machine 12, and the movable die 11 is arranged to be reciprocated on any type of suitable slide. The screw blanks 13 are fed from any suitable hopper mechanism down the slide 14, from which they are delivered one at a time to a position between the stationary and movable dies 10 and 11 respectively.

The preferred form of burring attachment as illustrated in Figs. 1 to 4 inclusive consists of a bracket 15 which is secured to the bed 12 of the machine by means of the screws 16 and 17. A block 18 is pivotally secured by means of the screw 19 to a downwardly extending arm 20 of the bracket 15. This block 18 is provided with a perforation

- 21 in which is placed a projecting pin integral with a file 22, said file being so located that it rests along the upper surface of the movable die 11. Any suitable scraper or abrading surface may be used in place of the file 22, but the best results will be obtained with a file the cutting edge or teeth of which are cut at an angle such as illustrated in Fig. 4. A file having the teeth cut in this manner—that is, a file in which the teeth are cut so that their cutting surfaces are angularly displaced with respect to the slot of the screw when said screw is in the position it assumes as it is rolled between the dies 10 and 11, will shave the burs from the head of the screw in a downward direction and this will eliminate any tendency to throw the bur back into the slot of the screw. A file or scraper of the type illustrated in Figs. 1 to 4 respectively will also avoid trouble which might otherwise be caused by the burring chips which might clog and fill up the grooves between the cutting edges or teeth of the file.
- 25 Secured to the downwardly extending arm 20 of the bracket 15 is a spring 24, the lower end of which forces the file, scraper, or other abrading surface 22 out over the top of the movable die 11 and about the pivotal center of the block 18. The file, scraper, or abrading surface 22 is held in position in the block 18 by means of the set screw 25, said set screw when loosened permitting rotation of the file in the block whereby the file can be adjusted to conform to the shape of the circumferential surface of any of the heads of the screws shown in Figs. 8 to 11 inclusive. The relative position of the scraper or file 22 with respect to the movable die 11 can be determined vertically by shifting the bracket 15 up or down on the bed 12 of the machine, the slots for the holding screws 16 and 17 in the bracket 15 being elongated, as indicated in Fig. 3. The bracket may be adjusted longitudinally—that is, the file or scraper 22 may be moved in toward the movable die 11 by placing suitable spacing plates between the mounting plate 26 of the bracket 15 and the frame 12 of the machine.
- 30 For coarser burring or scraping operations a coarser scraping surface than that provided by the file 22, shown in Figs. 1 to 4 inclusive, is required, and for these purposes a scraper such as shown in Figs. 5, 6, and 7 may be utilized. This scraper comprises a horizontal bracket 27 secured to the bed 12 of the machine, which bracket is tapped to receive the screw 28. Mounted on the bracket 27 by means of the screw 28 is a plate 29 fitted with an elongated slot 30. A plate 31 is secured to the lower edge of the plate 29 by means of the screws 32 and 33. The plate 31, as indicated in Figs. 5 and 6, comprises a plurality of forwardly projecting teeth 34, said teeth being given a taper when the

scraper is to be used for scraping the burs from flat headed screws, the angle of said taper conforming to the angle of the circumferential surface of the head of the flat headed screw. When this sort of a scraper 70 is used for screws of the type shown in Figs. 9 to 11 inclusive, the front edges of the teeth 34 are shaped at right angles to the top face of the plate 31, the front edge of the teeth under those circumstances being parallel to the faces of the dies 10 and 11. The bracket 27 is secured to the frame 12 by any suitable means, preferably by a screw which is fitted through a slot in the bracket 27, thereby providing for longitudinal adjustment of the 80 scraper. Vertical adjustment of the scraper is obtained by means of the screw 28 and the slotted perforations 30 in the plate 29.

In the operation of the machine, the screws are fed from the hopper down the 85 guide 14, from which they are fed one at a time to the dies 10 and 11. In the use of the preferred form of scraper illustrated in Figs. 1 to 4, the file or scraping surface 22 is first adjusted by means of the set screw 90 25, so that the abrading surface or the file 22 conforms to the head of the screw on which threads are being rolled and which is to be burred. If the screw is of the flat headed type, such as shown in Fig. 8 and 95 which is illustrated in position in the machine in Figs. 1 to 4 inclusive, the file is given an inclination such as shown particularly in Fig. 3, after which the set screw 25 is driven home to hold the file in place. 100 If the screws which are being threaded are of the type shown in Figs. 9 to 11 inclusive, the bracket 15 is raised and the file or scraper 22 is turned so that its abrading surface is parallel to the faces of the dies 11 and 10 and is likewise parallel to the flat peripheral edge of the fillister headed screw illustrated in Fig. 9, the button headed screw illustrated in Fig. 10, and the specially designed screw illustrated in Fig. 11. The 105 screws illustrated in Figs. 9 and 10 show the projecting burs 35 and 36 which are ordinarily produced in the slotting operation. The screw blank shown in Fig. 11 is formed in either a heading machine or a punch press, and in this operation it frequently occurs that a fin of the type 37 is formed on this head. This fin 37 is readily removed by the burring attachment when the file or scraper 22 is adjusted to its vertical position. 110 On the flat headed screws, such as illustrated in Fig. 8, a bur such as 38 is ordinarily generated in the slotting operation.

120 Returning now to the operation of the mechanism when the file or scraper 22 has been adjusted to conform to the shape of the head of the screw on which the bur is located and which is to be removed. The machine is started and the movable die 11 will roll the screws 13 forward between it and the 125 130

stationary die 10. In this operation the movable die will carry the head of the screw 13 over the surface of the scraper or file 22, and said scraper will cut off or abrade the bur projecting from the head of the screw. The scraper 22 is held in close contact with the head of the screw, which is being rolled, by the spring 24 which pushes the scraper about its pivot or screw 19 against the head of the screw that is being threaded. The scraper is consequently held in yielding contact with the screw as it passes between the stationary and movable dies, and this yielding contact compensates for any commercial variations in the dimensions of the screws and also for slight variations in the relative positions at which the screws are caught between the stationary die 10 and the movable die 11. It will be evident, therefore, that as the screws are threaded between the movable and stationary dies 11 and 10 respectively, the scraper or abrading surface 22 will remove from the heads of said screws any and all burs or fins formed thereon in the process of manufacturing the blanks, which burs may be produced either in the forming operation or in the slotting operation of the blank.

Obviously the invention is not limited to the specific embodiment thereof herein illustrated and described, but is capable of many variations and applications within the spirit and scope of the invention as set forth in the appended claims.

35 What is claimed is:

1. In a device of the character described, in combination, a stationary die, a movable die operable to propel screws between said dies and roll threads thereon, and an adjustable abrading means located above said movable die said means serving to remove burs and fins from the heads of said screws.
2. In a combined thread rolling and burring machine, in combination, a machine

frame, a stationary die and a movable die 45 mounted in said frame said movable die being operable to propel screws between said dies and roll threads thereon, a mounting means secured to said frame, and an abrading means pivotally secured to said mounting means and adapted to engage the heads of said screws as they are rolled between said dies to remove burs and fins therefrom.

50 3. In a combined thread rolling and burring machine, in combination, a machine frame, a stationary die and a movable die mounted in said frame said movable die being operable to propel screws between said dies and roll threads thereon, a mounting means secured to said frame, an abrading means pivotally secured to said mounting means and adapted to engage the heads of said screws as they are rolled between said dies to remove burs and fins therefrom, and means to adjust the angular position of said 55 abrading means to conform to the shape of the head of the screw.

60 4. In a device of the character described, in combination, a stationary die, a movable die operable to propel slotted screws between 70 said dies and roll threads thereon, and an abrading means located above said movable die said abrading means having cutting surfaces angularly placed with respect to the slot in the screw.

75 5. In a device of the character described, in combination, a stationary die, a movable die operable to propel slotted screws between said dies and roll threads thereon, and a pivoted file mounted above said movable die, the cutting edges or teeth of said file being angularly placed with respect to the slot in said screw.

In witness whereof, we hereunto subscribe our names this 14th day of November, A. D., 85 1917.

ISAAC W. ATCHISON.
FREDERICK M. STEIMER.
